UNITED STATES PATENT OFFICE

2,392,587

HEATING APPARATUS

Bernard Goerg, Bronxville, N. Y., assignor to
 American Radiator & Standard Sanitary Corporation, New York, N. Y., a corporation of Delaware

Application June 10, 1942, Serial No. 446,473

6 Claims. (Cl. 110—97)

My invention relates to heating apparatus such as boilers, furnaces, and the like, and it has for a broad object to provide a new and improved form of baffle structure which functions to direct the flow of the combustion gases and to protect the defining walls of the combustion chamber.

A further object is to provide an improved form of crown sheet baffle for heating apparatus which is simple in form and is inexpensive to make and which can be readily inserted and taken out through the furnace door and which can be easily and readily assembled in its operative position.

The invention consists in the novel construction and combination of parts, to be more fully described hereinafter, and the novelty of which will be particularly pointed out and distinctly claimed.

In the accompanying drawings, to be taken as a part of this specification, I have fully and clearly illustrated a preferred embodiment of my invention, in which drawings—

Fig. 1 is a longitudinal vertical section showing one preferred embodiment of my invention, the view being taken on the broken section line 1—1 of Fig. 2 and also including the lower part of the combustion chamber and a conventional form of fuel-burning apparatus;

Fig. 2 is a transverse vertical section taken on the line 2—2 of Fig. 1 and omitting the lower part of the combustion chamber;

Fig. 3 is a partial plan section taken on the line 3—3 of Fig. 1;

Fig. 4 is a detail view showing in perspective one of the plate members which when assembled with another plate member similar to the one shown, forms a crown sheet baffle; and

Fig. 5 is an enlarged fragmentary vertical section taken on the line 5—5 of Fig. 3.

Referring now in detail to the construction illustrated, I have shown my invention as embodied in a conventional form of heating apparatus, known in the art as a vertical sectional cast iron boiler. It will be appreciated, however, that, in so far as the broader aspects of this invention are concerned, it is not limited in its application to the particular type of boiler, or furnace, which is shown, for the invention can equally as well be incorporated in a variety of other types of heating apparatus.

In the drawings, the boiler is indicated in its entirety by the reference numeral 10 and comprises the usual back section 11, front section 12, and one or more intermediate sections, there being two in the boiler disclosed, said sections being indicated by the numerals 13 and 14, respec-

tively. The several sections are assembled in vertical side-by-side relation and the hollow interior spaces therein are connected at their lower ends by the usual small water flow nipples 15 (only one being shown) and at their upper ends by large steam and water flow nipples 16, so that the boiler water may freely circulate between sections and the steam from all sections may flow freely to a steam outlet connection 17 which may be formed in any desired section, for example, the intermediate section 14. The normal water level is indicated at 18. The boiler 10 may be operated as a hot water boiler as well as a steam boiler.

15 The several boiler sections are constructed so that when they are assembled in the manner shown, they provide a combustion chamber 20 in the lower part of the boiler, and a plurality of horizontal flues 21 in the upper part of the boiler to receive the combustion gases from the combustion chamber through the usual opening 22, here shown as being located in the top and rear of said chamber. The flues discharge such gases from the boiler through the usual smoke outlet 23.

20 The combustion chamber 20 is defined by a pair of opposed upright side walls 24 and 25, respectively, a crown sheet or top wall 26 connecting the upper ends of the side walls 24 and 25, and a pair of opposed end walls 27 and 28, respectively, connected at their upright sides to the side walls 24 and 25 and at their top to the crown sheet or top wall 26. The end wall 27 may be considered as the rear end wall and the end wall 28 as the front end wall of the combustion chamber. The gas outlet opening 22 is here shown as being provided in the top wall 26 adjacent the rear end wall 27. Although I have shown only one gas outlet 22, it will be appreciated that a second outlet is located at the opposite side of the combustion chamber and connecting the latter with the left-hand flue 21, as viewed in Fig. 2. Access may be had to the interior of the combustion chamber through the usual door 29 attached to the front end wall 28.

25

40 The boiler 10 is shown in Fig. 1 as being fired by a conventional gun type oil burner 30 which discharges a mixture of atomized oil and air into the lower part of the combustion chamber where it is ignited and the major part of combustion takes place. As stated, the combustion gases flow upwardly and outwardly from the combustion chamber through the outlet opening 22. The arrows in Fig. 1 indicate the path of flow of the combustion gases.

45

50 In accordance with the present invention, I

provide an improved form of crown sheet baffle structure indicated generally by the reference character 32. The baffle is spaced downward from the crown sheet or top wall 26 and from the gas outlet 22 and thereby functions to prevent the very hot combustion gases from flowing directly to the gas outlet and also effects a more thorough and intimate contact of the gases with the entire area of heat absorbing surface defining the combustion chamber. Due to this well distributed and intimate contact of the gases with the heat absorbing wall structure, the temperature of the gases leaving the combustion chamber is lower and the efficiency of the boiler higher. Furthermore, the baffle structure 32 acts to reduce the temperature of the gases before striking the top wall or crown sheet 26 and consequently there is less likelihood of damage to the crown sheet, the latter being more vulnerable to high temperatures due to the flues 21 obstructing to some extent the circulation in the water space above the crown sheet.

The crown sheet baffle structure 32 extends across the top of the combustion chamber from one side wall 24 thereof to the other side wall 25 and is arranged alongside the end wall 27 which is adjacent the outlet 22. As stated, the baffle 32 is spaced downward from the top wall 26 and is arranged beneath the outlet 22 and thus provides a gas passage 33 between the wall 26 and baffle 32, which passage connects at its forward end with the upper parts of the combustion chamber and connects at its rear end with the outlet 22.

The baffle 32 is shown as being composed of two similar rectilinear-shaped thin plate members 34 and 35, respectively, and the two plate members are so arranged with respect to one another that they form an inverted V-shaped structure, or, if preferred, the shape of the baffle structure may be likened unto the peaked roof of a house with each plate corresponding to a side of the roof and lying adjacent one of the upright side walls. The apex of the V-shaped structure is shown as extending forwardly away from a central portion of the rear end wall 27 and toward the front end wall 28 and lying approximately within a central longitudinal vertical plane through the boiler and about equidistant from the two side walls 24 and 25.

Each of the plate members 34 and 35 is formed as a casting and the plates are preferably identical in form so that only one pattern will be required. The plates are so constructed that they may be arranged adjacent either of the upright side walls 24 or 25, i. e., they are reversible. Each plate comprises a lower edge portion 37 adapted to be arranged alongside one of the side walls and an upper edge portion 38 arranged in abutting and mutual supporting engagement with the upper edge 38 of the other plate, and each plate comprises end or lateral edge portions 39 and 40, one of which extends along the end wall 27, depending upon which side of the boiler the plate is placed. The various edge portions contribute to reinforcing the plate.

Means is provided on each of the upright side walls 24 and 25 at opposite sides of the combustion chamber for supporting the lower edge portions 37 of the two plate members against outward or downward movement, said means being shown in the form of a single lug 42 extending inwardly from each side of the section 13 and an abutment member 43 arranged centrally and on

top of each lug 42. The outer or peripheral face of each lower edge portion 37 abuts a member 43 and the lowermost edge 37a thereof rests on the lug 42 (see Fig. 5). As corresponding upper edge portions 38 of the two plates are in abutting engagement with one another and the lower edge portions 37 are prevented from spreading or moving outward due to lugs 42 and abutments 43, the two plates are held together in assembled position by their own weight. The lugs 42 engage the respective plates forwardly of their longitudinal centers whereby the plates are caused to lean against the rear furnace wall as later described.

In order to assure proper assembly of the plates within the boiler and at the same time permit reasonable tolerances in manufacture of the cast iron parts, the upper edge portion 38 of each plate is provided with a relatively high abutting or engaging surface preferably in the form of a relatively high flange 45 having an outer abutting face 46. It is noted from an examination of Figs. 1, 3, and 4 that the abutting face 46 does not extend for the full length of the flange 45, but is in reality two co-planar faces 46a and 46b located, respectively, at the two end portions of the flange 45. The central portion 47 of the flange does not extend out to the plane of the faces 46a and 46b. The latter is done so as to assure abutting engagement of the faces of opposing plates 34 and 35. If the face 46 extended for the full length of the flange, unevenness in casting might cause a high spot and engagement would only be had at that spot and the plates would rock about the point of engagement and be unsteady. The construction shown assures at least two points of contact at opposite ends of each plate.

Each of the plates 34 and 35 is provided at its upper edge 38 with a pair of hooks, or lugs, 49 and 50, which project outwardly from the flange 45 thereof and overlie the top surface of the flange 45 of the other plate. Thus, in case either plate, for example, the plate 34, happens to be accidentally displaced upwardly with respect to the other plate, the plate 35, the hooks 49 and 50 of plate 35 will immediately engage the top surface of flange 45 of plate 34 and hold the latter against further upward movement and disassembly of the plates. In order to provide tolerances in the castings necessary to assure their operative assembly, a slight space is shown between the lower surface of the hooks and the top surface of the flange 45 of the opposing plate. In order that only one pattern be necessary, the hooks 49 and 50 of each plate are spaced unequal distances from the adjacent edges 39 and 40 thereof, so that when the plates are arranged in reverse position with respect to one another, the position shown in the drawings, the hooks of one plate will be staggered with respect to the hooks of the other plate and will not strike one another. It is noted that in Fig. 3 the right-hand hook 50 is spaced the same distance from the right-hand edge 40 of plate 35, as the left-hand hook 50 is spaced from the left-hand edge 40 of its plate 34. Also the left-hand hook 49 is spaced the same distance from the adjacent edge 39 of its plate 35 as the right-hand hook 49 is spaced from the adjacent edge 39 of its plate 34. But, the right-hand hook 50 is closer to the adjacent edge of plate 35 than the left-hand hook 49 of plate 35 is to its adjacent edge, and the same relation is true with respect to hooks 49 and 50 of plate

34. The difference in spacing is such that the hooks of opposing plates will not interfere with one another and so that the hook 49 of one plate will always lie alongside the hook 50 of the adjacent plate.

Each end edge portion 39 and 40 is provided adjacent the upper and lower edges 38 and 37 with spacing lugs 52 and 53, so that when either plate is in assembled operative position the lugs 52 and 53 projecting from the end edge portion thereof which is adjacent the rear end wall 27, will engage such wall 27 and space such end edge portion therefrom, so that a small flow of combustion gases will be maintained upward along the surface of wall 27 and into the gas outlet 22. This construction prevents the formation of dead gas spaces along the wall 27 beneath the baffle 32. These lugs also position the plates and prevent them from rotating about their single lower edge lug supports 42.

Each of the plates 34 and 35 is also provided along the lower longitudinal edge 37 thereof with downwardly extending lugs 60 one of which engages behind the side of the projection or lug 42 which is adjacent the end wall 27 and holds such plate in assembled position against and prevents it moving away from the end wall. One of the lugs 60 performs the just mentioned function when the plate is arranged alongside one boiler side wall and the other lug 60 performs such function when the position of the plate is reversed and it is arranged alongside the opposite boiler side wall.

From the foregoing, it will be apparent that I have provided an improved form of heating apparatus which includes as an essential part thereof, a simple and inexpensive form of crown sheet baffle, which can be readily inserted through a fire door and properly assembled in the combustion chamber after the boiler sections have been assembled.

What I claim and desire to secure by Letters Patent of the United States is:

1. A crown sheet baffle for boilers and the like comprising a pair of similar thin plate members arranged to form an inverted V-shaped structure with the upper meeting edges of said members in abutting mutual supporting engagement, and adapted to be supported at their lower outer edges against outward and downward movement, each of said plate members being generally rectangular in shape and including a wide upstanding reinforcing flange extending along one side thereof and having an outer face forming said upper meeting edge thereof, said face having coplanar end portions and a depressed center portion and each member also including two hook-like lugs projecting along the back of and outward from the top of said flange one near each end thereof and adapted to overlie the adjacent parts of said other plate member when in assembled relation therewith, said lugs being differently spaced from their respective ends for the purpose described.

2. In heating apparatus, wall structure defining a combustion chamber wherein fuel is adapted to be burned and including upright opposed side walls, a rear wall and a top wall; a crown sheet baffle extending across said combustion chamber from one side wall thereof to the opposite side wall thereof, having one edge substantially against the rear wall and being spaced downwardly from said top wall to provide a gas passage therebetween, said crown sheet baffle comprising a pair of similar plates arranged

to form an inverted V-shaped structure and each plate comprising upper and lower edge portions at opposite sides thereof and the lower edge portion arranged substantially horizontally alongside one of said side walls and the upper edge portion being arranged centrally of said chamber and being provided by an upstanding flange of substantial height having an outer face disposed in abutting and mutual supporting engagement with the corresponding face of the other plate, a single lug on each of said side walls for supporting, respectively, the lower edges of said plates only forward of their longitudinal centers against outward and downward movement and means on each lower edge to engage behind the corresponding lug to prevent movement of the plate away from the rear wall.

3. In heating apparatus, wall structure defining a combustion chamber wherein fuel is adapted to be burned and including a pair of upright

20 opposed side walls, a rear wall and a top wall; a pair of supporting lugs formed, respectively, one on each of said side walls and said lugs extending toward the center of the combustion

25 chamber; a crown sheet baffle extending across said combustion chamber from one side wall thereof to the opposite side wall thereof, having one edge engaging against the rear wall and being spaced downwardly from said top wall to provide a gas passage therebetween, said crown sheet baffle comprising a pair of similar plates arranged to form an inverted V-shaped structure and each plate comprising upper and lower

30 edge portions at opposite sides thereof and the lower edge portion being arranged alongside one of said side walls and being supported by the lug on said one side wall only forward of the longitudinal center thereof against outward and downward movement and the upper edge portion of each plate being disposed centrally of said

35 chamber and in abutting and mutual supporting engagement with the upper edge portion of the other plate.

4. In heating apparatus, upright opposed side

45 walls, an end wall, and a top wall constituting a part of the defining wall structure of a combustion chamber in which fuel is burned, the combustion chamber having a gas outlet in the upper part thereof adjacent said end wall; a crown sheet baffle extending across the upper part of

50 the combustion chamber from one side wall to the other side wall and alongside said end wall and being spaced downwardly from said top wall and below said outlet to provide a gas passage connected at one end with said outlet and connected at its other end with the lower part of

55 the combustion chamber, said crown sheet baffle comprising a pair of similar plates arranged to form an inverted V-shaped structure with the apex of the V extending horizontally outward from said end wall and lengthwise of the combustion chamber and being located approximately equidistant from the side walls, each plate having an upper edge in abutting and mutual supporting engagement with the corresponding upper

60 edge of the other plate and a lower edge alongside the adjacent side wall, means on said side walls and engaging the lower edges of said plates substantially forward of their longitudinal center for supporting said plates against outward and downward movement, and lugs spacing said plates from said end wall so as to permit enough

65 gas flow therebetween to prevent a dead gas space below the plates and alongside the end wall, said last mentioned lugs preventing rotation of the 70 plates about the first lugs.

5. In heating apparatus, wall structure defining a combustion chamber wherein fuel is adapted to be burned and comprising upright opposed side walls, an end wall, and a top wall; a pair of supporting lugs formed, respectively, on said side walls and said lugs extending toward the center of the combustion chamber, a crown sheet baffle extending across the upper part of the combustion chamber from one side wall to the other side wall and arranged alongside and in engagement with said end wall and said baffle being spaced downwardly from said top wall to provide a gas passage therebetween, said crown sheet baffle comprising a pair of similar plates arranged to form an inverted V-shaped structure and each plate comprising upper and lower edge portions at opposite sides thereof and the lower edge portion being arranged alongside one of said side walls and being supported by said lug on said one side wall against outward and downward movement, and the upper edge portion of each plate being disposed centrally of said chamber and in abutting and mutual supporting engagement with the upper edge portion of the other plate, and a positioning lug projecting from the lower parts of each plate and engaging the side of the adjacent supporting lug which faces toward said end wall so as to hold the plate in engagement against said end wall.

6. In heating apparatus comprising opposed upright side walls, a front wall, a rear wall, and a top wall defining a combustion chamber in which fuel is adapted to be burned, a removable crown sheet baffle adapted to be arranged across the upper part of said combustion chamber from one side wall to the other side wall thereof and spaced downwardly from said top wall to define a gas passage therebetween, and said crown sheet baffle comprising a pair of similar interchangeable plates arranged to form an inverted V-shaped structure with the apex of the V extending horizontally between the front and rear walls and being located approximately equidistant from the side walls, each of said plates having an upper edge in abutting and mutual supporting engagement with the upper edge of the other plate and having a lower edge lying alongside the adjacent side wall, means on said side walls supporting the lower edges of said plates forward of their longitudinal centers against outward and downward movement, and projections forming substantial extensions of the upper and lower edges of each plate engaging the rear wall to provide spacing therefrom and to prevent rotation of the plates about said supporting means.

BERNARD GOERG.
